UNITED STATES PATENT OFFICE.

AKSEL VILHELM PERSSON, OF ESSINGTON, AND PEDER ROSLUND MÅNSSON, OF PHILADELPHIA, PENNSYLVANIA.

WINDSHIELD PROTECTOR.

Application filed May 20, 1924. Serial No. 714,543.

To all whom it may concern:

Be it known that we, AKSEL VILHELM PERSSON and PEDER ROSLUND MÅNSSON, both subjects of the King of Denmark, and 5 residents of Essington, county of Delaware, State of Pennsylvania, and Philadelphia, county of Philadelphia, and State of Pennsylvania, respectively, have jointly invented certain new and useful Improvements 10 in Windshield Protectors, of which the following is a full, clear, and exact description.

This invention relates to a new and useful improvement in windshield protectors, 15 and has for its object to provide a device which attached to the frame of the windshield, in front of this, will prevent snow and rain from striking the glass and thereby secure to the chauffeur a clear front 20 view at all times.

With the above and other objects in view the invention consists of the novel features of construction, combination and arrangements of parts hereinafter fully described 25 and claimed and illustrated in the accompanying drawings forming part of this specification, in which similar characters of reference indicate corresponding parts in all views, and in which:—

30 Figure 1 is a perspective view of an embodiment in part of our invention; Fig. 2 is a transverse vertical section taken on line A—A of Fig. 3; Fig. 3 is a rear elevation; Fig. 4 is a perspective view of the lower 35 section of our device; Fig. 5 is a detail sectional view of same, and Fig. 6 shows the device applied in practice to an automobile.

This invention consists of two sections, B and C, operating in conjunction, although 40 the upper section B, might in some cases be used alone.

Referring in detail to the drawings, B designates the upper part or body of our 45 device a windshield protector, or storm-deflector, preferably made of thin sheet metal, although it may be made of any other suitable material.

It has a top plate 11 having a convex or 50 curved outer surface, the lower part of said plate being bent upon itself to form a small groove or channel 12. Below said top plate is secured a member 13, constructed with a slight curvature and inclined at an angle of about 45° to the horizontal. This member 55 besides being bent upon itself as indi-

cated at 14 has both ends bent into small channels or grooves as designated by the numerals 15 and 16.

Said members 11 and 13 have on each side 60 rigidly secured side plates 17, which extend a considerable distance to the rear of said members as indicated at 17a; these elongated parts of said side-plates have a top cover or roof 18, which in conjunction with said elongated side plates serve as a spacer to bring 65 said storm-deflector in right operating position relative to the windshield; this projecting rear part of our device is also provided with means for securing same to the upper 70 frame of the windshield; said means consist in having these rearwardly projecting plates 17a and 18 bent upon themselves at a right angle to form a flange 19; to this flange are secured metal hangers 20 adapted to be 75 hooked unto the upper frame of the windshield. To provide a tight and snug fit we have provided on said flanges at their inner side extending over their entire length a 80 metal groove 21, wherein is tightly fitted a heavy rubber band 22, which, when our device is brought into operation, absorbs 85 shocks and jerks that might otherwise be imparted to the glass of the windshield by said mechanical structure. Other means may be employed to secure said device to the 90 windshield, especially when said device is made the same width as the windshield and not merely sectional, covering only the space in front of the chauffeur.

The side plates 17 are provided with apertures 23, 24 and 25 forming outlets for the 95 corresponding grooves 12, 16 and 15.

As shown in Fig. 1, the position of the members 11 and 13 relative to one another is such as to provide a space between them or to form a funnel, which in connection 100 with the inclined position of member 13 and the slightly concave lower surface of same will provide an aerial suction and deflect the rain and snow so that the windshield or the section thereof used by the chauffeur will not be affected at all by such weather conditions.

This object is further accomplished 105 through the construction of aforesaid grooves 12, 16 and 15 in which rain and snow after striking the members 11 and 13 will accumulate, whereafter the water is carried off through the outlets 23, 24 and 25.

To make our device still more effective 110

we have constructed for use in conjunction with aforesaid section B, another section C, consisting of preferably a rectangular plate of heavy glass 26, which is enclosed in the 5 usual metal frame as indicated at 27; said frame is pivotally hinged to the lower part of the stationary windshield in any suitable manner. As shown in Fig. 5, we prefer to have the lower ends of the side frames 27 10 elongated with enlarged portions having eyelets 28, and studs 29 secured to the frame of the stationary windshield and projecting to receive said eyelets.

Rigidly secured to the windshield on each 15 side are two projecting guides 30 having slots 31, which permits free sliding movement of an adjustment screw 32 secured to each side of said glass frame. To bring the latter in any desired position the head of 20 said adjustment screw 33 is turned inwardly, thereby securing a compact juncture of the glass frame and the guides in any position.

It is obvious that while the section B itself affords ample protection from rain and snow 25 for a part of the windshield, such protection becomes most complete in conjunction with the operation and adjustment of section C.

While we have shown and described the 30 preferred construction and arrangement of the several elements employed, it will be understood that the invention is susceptible to considerable modification therein without departing from the spirit and scope of the appended claims.

Having thus described the invention we claim as new, and desire to secure by Letters Patent:—

1. A windshield protector comprising a 40 casing, a means for securing said casing to a windshield, a curved top for said casing having a channel formed therewith, a deflector plate in said casing spaced from said top and acting in conjunction therewith as 45 a funnel providing for aerial suction, said deflector plate formed with a plurality of channels, all of said channels acting as rain and snow catchers, and means of draining said casing.

2. A windshield protector comprising a 50 casing, a convex, rearwardly curved top plate for said casing having a channel formed therewith, side plates for said casing, said side plates provided with a plurality of drainage openings, a rearwardly 55 directed extension on said casing, means on said extension for securing the casing to a windshield, a curved deflector plate within said casing bent upon itself and formed with channels at its ends, all of said channels

constituting rain and snow catchers and communicating with the openings in said side walls for allowing a draining of the casing, and cushioning means for the securing means. 65

3. A windshield protector comprising a 70 casing, perforated side walls for said casing, a rearwardly curved top formed with a channel at its lower end, a rearward extension on said casing, a grooved flange on said extension, hangers attached to said flange for securing the casing to a windshield, a rubber cushion in the groove of said flange 75 for preventing rattling, and a curved and inclined deflector plate within said casing having its material bent upon itself and channels formed at its ends, said curved deflector plate and top providing a funnel for aerial suction, and said channels communicating with the openings in the said walls 80 forming automatically acting drainage means.

4. A device of the character described 85 consisting of two co-operating sections, an upper and a lower one, the said upper section comprising a casing rearwardly extended and provided with means for securing the same on a windshield, means for cushioning said securing means, a rearwardly directed curved top plate for said 90 casing, having a channel formed with its lower end, a curved and inclined deflector plate within the casing in spaced relation to the top thereof, having channels formed with its ends, all of said channels communicating with openings in the side walls of said casing allowing an automatic draining of the same. 95

5. A windshield protector comprising a 100 casing, open at its front, a top plate for said casing having an outer, convex front and a straight rear extension, perforated side plates for said casing, a flange at the rear end of said casing having an outer groove, a rubber cushion within said groove adapted 105 to engage the windshield, hangers attached to said flange for securing said casing on a windshield, said top plate having a channel formed at its lower end in communication with one of the openings in the side walls, 110 a curved and inclined deflector plate having its material bent upon itself within said casing and channels formed at its ends communicating with openings in the side walls, and a means co-operating with said casing for 115 forming a complete windshield protecting device.

AKSEL VILHELM PERSSON.
PEDER ROSLUND MÅNSSON.
